[57] CLAIM

The ornamental design for a combined mug and megaphone, as shown and described.

DESCRIPTION

FIG. 1 is a side elevational view of a combined mug and megaphone showing my new design;

FIG. 2 is a side elevational view rotated by 90° from FIG. 1;

FIG. 3 is a bottom plan view thereof;

FIG. 4 is a top end plan view thereof; and

FIG. 5 is a cross sectional view taken substantially along the plane of line 5—5 in FIG. 1.
